F. M. HALE,
EXPLOSIVE SHELL OR SIMILAR BODY,
APPLICATION FILED MAR. 12, 1919.

1,303,197.

Patented May 6, 1919.

FIG. 1.

FIG. 2.

Frederick Martin Hale
by his attorney
A. Parker Smith

UNITED STATES PATENT OFFICE.

FREDERICK MARTEN HALE, OF BROMLEY, ENGLAND.

EXPLOSIVE SHELL OR SIMILAR BODY.

1,303,197.

Specification of Letters Patent.

Patented May 6, 1919.

Application filed March 12, 1919. Serial No. 232,211.

To all whom it may concern:

Be it known that I, FREDERICK MARTEN HALE, a subject of the King of Great Britain and Ireland, and a resident of Bromley, in the county of Kent, England, have invented certain new and useful Improvements in or Pertaining to Explosive Shells or Similar Bodies, of which the following is a specification.

- 10 This invention relates to explosive shells or similar bodies (hereinafter referred to as shells) intended to be dropped or discharged from aircraft, and preferably of the type in which there is provided mechanism adapted 15 to prevent a detonator arranged in the rear portion of the shell from being, by the impact of the shell against an object, moved forward against a fixed firing element before the shell has traveled a predetermined distance through the air.

For the purpose of adapting such a shell for submarine attack by securing that the detonator of the shell shall not be free to move forward on impact until after the shell 25 has struck the water, according to this invention, there are arranged in the shell spring catches adapted to engage the detonator so as to prevent forward movement thereof until they have been released by a sleeve which surrounds them and is adapted on the impact of the shell against the water to be moved forward by its inertia into such a position as to free the catches, which are adapted then to liberate the detonator. 30 Suitable means are, or may be, provided to prevent the sleeve from accidentally moving forward so as to liberate the catches for holding back the detonator.

To enable the unlocking of the detonator 40 by the impact of the shell against the water to be easily and quickly dispensed with when desired, so as to adapt the shell to be fired by impact above water, at or just below the surface of the water, or on land, there may 45 be provided means for enabling the sleeve to be placed and held in a position such that the catches for holding back the detonator are freed by it and consequently do not engage with the detonator.

50 For preventing the detonator from being, by the impact of the shell against an object, moved forward against a fixed firing element before the shell has traveled a predetermined distance through the air, the particular mechanism hereinafter described

may be employed, or any other suitable arrangement of parts.

The invention, the various features of which are defined in the claiming clauses hereof, is illustrated by the accompanying 60 drawings, of which Figure 1 is a longitudinal section of an example of a shell constructed according thereto and Fig. 2 is a cross section drawn to a larger scale than Fig. 1 and corresponding chiefly to the line 65 II thereof.

1 is the body of the shell and 2 the detonator. To secure that the detonator shall not be free to move forward on impact until after the shell has struck the water, there are 70 arranged in the shell spring catches 3 adapted to engage the detonator 2 so as to prevent forward movement thereof until they have been released by a sleeve 4 which surrounds them and is adapted on impact of the shell 75 against the water to be by its inertia moved forward in relation to the body 1 into such a position as to free the catches, which are adapted then to liberate the detonator; the catches 3 have washers 5 which are arranged 80 to be pressed by collars 6 against collars 7 in order to prevent access of water at the catches. To prevent the sleeve 4 from accidentally moving forward so as to liberate the catches 3, a spring 8 is arranged to press 85 it normally rearward against a pin 9 (Fig. 2) secured in the body 1 of the shell.

To enable the unlocking of the detonator by the impact of the shell against the water to be easily and quickly dispensed with, so 90 as to adapt the shell to be fired by impact above water, at or just below the surface of the water, or on land, the sleeve 4 is formed with two notches 10 and 11 (Fig. 2) to receive the pin 9 and also with two notches 12 95 (Fig. 2) adapted to receive the outer ends of the catches 3 when the pin 9 is in the notch 11, so that if the sleeve 4 be pressed forward against the spring 8 it can be turned from the position shown in the drawings 100 into a position which will allow the catches 3 to enter the notches 12 and consequently disengage the detonator 2 and in which the sleeve 4 will be held by the engagement of the pin 9 in the notch 11; the two notches 105 10 and 11 are, of course, only sufficiently deep to enable the pin 9 to engage satisfactorily therein, so that to turn the sleeve 4 from one position to the other only a slight compression of the spring 8 is required. 110

The mechanism provided in the example for preventing the detonator from being, by the impact of the shell against an object, moved forward against a fixed firing element before the shell has traveled a predetermined distance through the air, is, as is preferred, substantially such as described in the specification of prior application for U. S. patent, Serial No. 268,156, filed December 24, 1918, allowed January 14, 1918. This device comprises a spindle 17, threaded into a recess in the rear of the detonator 2, but adapted to be disengaged therefrom by rotation and withdrawal produced by action of the helical wings 18, mounted on the rear of the spindle 17. Split pin 19', normally prevents this rotation, but before dropping the bomb this pin is withdrawn and when the bomb is dropped the wings 18, revolve, rotating spindle 17, in a direction that will free it from the detonator, and leaving the latter restrained solely by radial pins 3, 3, which mesh with any suitable engaging means on the detonator, such as shoulder 19. These pins are normally forced outward by springs 20, so as to free them from shoulder 19, but may be restrained in meshed position therewith by the surrounding sleeve or collar 4. When the shell strikes the water and its forward motion is retarded thereby, collar 4, continues to move forward, by its inertia, compressing spring 8. After a given interval of time, dependent on the relation of the weight of the collar to the resistance of spring 8, the pins 3, are uncovered by the continued motion of collar 4, then are forced out by springs 20, and the detonator is left free to be moved forward relatively to the shell by its inertia, and to explode the charge in the front of the shell.

Washers 14, 15 and 16, serve to render the joints in the rear of the casing all fluid tight, after the spindle 17, has been withdrawn and the detonator liberated as first above described.

What I claim is:—

1. In an explosive shell suitable for dropping from an aircraft and similar purposes the combination, with the usual container and explosive charge therein, of a detonator movable relative to the charge and provided with engaging means, radially movable locking pins mounted in the container and cooperating with said engaging means, a sleeve normally holding said pins in mesh with the engaging means, but capable of moving far enough toward the explosive charge to free said pins, and springs arranged to force said pins out of engagement as soon as they are released by the sleeve.

2. A structure such as set out in claim 1, in combination with a spring normally holding the sleeve in engagement with the pins, but so placed as to be overcome and flexed by the inertia of the parts sufficiently to

allow the sleeve to free the pins when the motion of the shell is checked.

3. A structure such as set forth in claim 1, combined with means for holding said sleeve out of engagement with the pins, whereby the pins may be freed from mesh with the engaging means of the detonator before the shell is started on its flight.

4. In an explosive shell suitable for dropping from an aircraft and similar purposes the combination, with the usual container and explosive charge therein, of a detonator movable relative to the charge and provided with engaging means, radially movable locking pins mounted in the container and cooperating with said engaging means, when in their inmost position, shoulders on said pins, seats in the casing toward which said shoulders are forced when the pins move outward to free themselves from the engaging means on the detonator, and means for forcing said pins outward till the detonator is so freed and the pin shoulders seat themselves in the casing, whereby when the detonator is thus released the pin chambers are sealed against the entry of any fluids in which the shell may then be immersed.

5. In an explosive shell the combination, with the shell casing having a radial passage therethrough and a movable detonator mounted in the casing transversely of the said passage; of a movable pin mounted in said radial passageway, engaging and holding the detonator against movement, a spring tending to force said pin outward, a flange on the pin, an annular seat in the outer end of the passage toward which the pin and flange are forced by the spring, a gasket surrounding the pin and located between said seat and flange, and means for alternately holding said pin in its inmost position and releasing it to be moved outward by its spring to free the detonator, whereby the gasket is compressed between flange and seat and the radial passage thereby sealed against the entry of fluid whenever the detonator is released.

6. An explosive shell adapted to be discharged from aircraft and comprising in combination a body, a rear firing element located in said body, a front firing element arranged in said body in advance of said rear firing element, means for normally restraining said rear firing element from moving forward against the front firing element, an inertia appliance adapted to normally keep said restraining means in engagement with the rear firing element but capable of moving forward and eventually freeing said restraining means, and means acting throughout any such forward movement of said inertia appliance to resist said movement; whereby upon impact of the shell on the water said inertia appliance begins to move forward gradually and thereby liber-

ates said restraining means after a substantial period of time, so that the rear firing element is then free to move forward against the front firing element and explode the shell after the same is completely submerged in the water. 5

7. An explosive shell adapted to be discharged from aircraft and comprising in combination a body, a rear firing element located in said body, a front firing element arranged in said body in advance of said rear firing element, mechanism adapted to prevent said rear firing element from being, by the impact of said shell against an object, moved forward against said front firing element before the shell has traveled a predetermined distance through the air, additional means for normally restraining said rear firing element from moving forward 10 against the front firing element, an inertia appliance adapted to normally keep said additional means in engagement with the rear firing element but capable of moving forward and eventually freeing said additional 15 means, and means acting throughout any such forward movement of said inertia appliance to resist said movement; whereby upon impact of the shell on the water said inertia appliance begins to move forward 20 gradually and thereby liberates said additional means after a substantial period of 25

time, so that the rear firing element is then free to move forward against the front firing element and explode the shell after the same is completely submerged in the water. 35

8. An explosive shell adapted to be discharged from aircraft and comprising, in combination, a rear firing element located in said body, a front firing element arranged in said body in advance of said rear firing element, an inertia appliance, mechanism controlled by the inertia appliance for normally restraining said rear firing element from moving forward against said front firing element but eventually releasing the same upon completed movement of the inertia appliance, and means acting throughout any movement of the inertia appliance to resist such movement, but allowing it to be eventually completed; whereby upon impact 40 of the shell against the water the inertia appliance begins to move, but the completion of said movement and the consequent release of the rear firing element is not effected until the shell has become submerged in the water. 50 55

Signed at 75/77 Cornhill, London, England, this twenty-seventh day of November 1918.

FREDERICK MARTEN HALE.
